UNITED STATES PATENT OFFICE.

HOWARD A. HANDS, OF WILKINSBURG, PENNSYLVANIA, ASSIGNOR TO WESTINGHOUSE ELECTRIC & MANUFACTURING COMPANY, A CORPORATION OF PENNSYLVANIA.

TERMINAL FOR RESISTORS.

Application filed October 28, 1922. Serial No. 597,530.

My invention relates to terminals and particularly to terminals for resistor elements used in heating furnace and appliances.

One object of my invention is to provide a resistor-terminal device wherein the terminal of the resistor is securely fastened to the terminal of the furnace in such manner as to provide an extensive area of contact and wherein surfaces of the resistor in contact with the furnace terminal are protected from the gases and high temperatures prevailing within the furnace.

Another object of my invention is to provide a simple terminal device wherein standard bolts and nuts may be used for securing a resistor terminal to a furnace terminal.

Another object of my invention is to provide a terminal device for resistors wherein the resistor may be attached to, and removed from, the furnace terminal with a minimum of effort and wherein a durable connection between the resistor terminal and the furnace terminal is obtained.

These and other objects, that will be made apparent throughout the further description of my invention, are attained by means of the apparatus hereinafter described, and illustrated in the accompanying drawings, wherein:

30 Figure 1 is a view, partially in section and partially in elevation, showing the terminal device with one of the parts in disassembled relation;

35 Fig. 2 is a view similar to that shown in Fig. 1, with the parts in assembled relation, and

Fig. 3 is an elevational view of the terminal of the resistor element.

Referring to the drawings, a furnace terminal 4 is shown having an opening 5 through which a threaded bolt 6 projects. The resistor or heating element 7, such as "chromel" wire is provided with a helically wound portion 8 disposed at one end thereof, the pitch of the turns of the helix corresponding to the pitch of the threads of the bolt to which the resistor is applied.

The diameter of the helix is such that the bolt may be screwed thereinto, as indicated in Fig. 1. Before the bolt is screwed into the helix of the resistor, a threaded nut 9 is placed upon the resistor in the position indicated in Fig. 1. After the bolt 6 has been threaded into the helix, the nut 9, which is

provided with a threaded opening 10 having 55 a pitch corresponding to that of the thread of the bolt and of sufficient diameter to screw upon the threads formed by the outer surfaces of the helix, is threaded upon the helix to a position shown in Fig 2. The 60 nut 9 serves both to securely clamp the helical portion of the resistor to the bolt and also to securely fasten the bolt to the terminal 4.

It will be seen that the construction provides a simple and inexpensive terminal device wherein a relatively large area of the resistor is securely clamped in intimate engagement with the threads of the bolt and the nut. The portions of the resistor lying 70 within the threads between the bolt and the nut are practically surrounded by metal and are protected from the gases and extreme temperatures prevailing within the furnace. This protection increases the life of 75 the resistor at the point of connection, and perfect contact is secured between the terminal bolts and the resistor, thereby preventing the oxidization of the bolt to the nut with the consequential difficulties in detaching them after continued use in contact with furnace gases.

While my form of terminal device is particularly adapted for attaching resistor elements of heating furnaces to the furnace terminals, it will be understood that the device is equally effective for connecting any form of electrical conductor to any form of terminal in which a bolt-and-nut construction may be used.

While I have described and illustrated but one embodiment of my invention, it will be apparent to those skilled in the art that various changes, modifications, substitutions, additions and omissions may be made in 95 the apparatus illustrated without departing from the spirit and scope thereof, as set forth in the appended claims.

I claim as my invention:

1. The combination with a threaded terminal member, of a conductor having a helically wound portion fitting the threads of the member and a threaded binding nut fitting the helically wound portion of the conductor for securing the conductor in conductive contact with the member.

2. The combination with a terminal member and a threaded terminal bolt, of a con-

ductor having a helically wound portion fitting the threads of the bolt and a threaded binding nut fitting the helically wound portion of the conductor for securing the bolt to the terminal member and the conductor to the bolt.

3. The combination with a threaded terminal bolt, of a helically wound portion fitting the threads of the bolt and having the turns of the helix corresponding in pitch

to that of the threads and a threaded binding nut fitting the helically wound portion and having threads of a pitch corresponding to that of the bolt and helical portion of the conductor.

In testimony whereof, I have hereunto subscribed my name this 17th day of October, 1922.

HOWARD A. HANDS.
